AUTOMATIC CARBURETOR CHOKE

Peter J. Jorgensen, deceased, late of Elmhurst, Ill., by Clarence H. Jorgensen, administrator, Anderson, Ind., and Clarence H. Jorgensen, Anderson, Ind.

Application April 30, 1934, Serial No. 723,284
Renewed April 16, 1938

23 Claims. (Cl. 123—119)

The present invention relates to automatic chokes for carburetors and the like and is particularly concerned with the provision of a carburetor control unit which is simple and inexpensive yet is capable of automatically controlling fuel mixtures in the carburetor to secure efficient carburetion under the widely varying conditions found in service. More specifically, it is an object of the present invention to provide an automatic carburetor choke control having means which is responsive, first, to the temperature of the motor, and second, the factor of whether or not the motor has actually started to run under its own power, in connection with means serving to prevent any sudden opening of the carburetor choke or air valve, whereby any sudden changes in the velocity of the air entering the carburetor will not displace the control effected by the responsive means or otherwise disturb the fuel ratio established thereby.

Another object of the present invention, particularly in connection with carburetors in which the air valve or choke valve is arranged to automatically open under increased air velocities, is the provision of a dash pot arranged to prevent sudden changes in air velocities, temporary irregularities of motor speed, and other factors from throwing the air valve out of proper position. Preferably, but not necessarily, the dash pot has suitable valve or other means so that the dash pot is operative only in one direction to restrain any sudden movement of the air valve, this direction being the opening movement of the valve. The dash pot is preferably arranged to allow substantially unrestrained closing movement of the air valve or choke valve and while the dash pot prevents any sudden opening of the valve, yet gradual movement of the choke valve to the proper open or partially open position is not interfered with. For example, when the engine is being cranked, particularly at low temperatures, the choke valve is normally closed, at least a substantial portion, and as soon as the engine begins to fire, the increased value of air drawn in through the carburetor tends to open the choke valve, and this opening of the valve tends to thin the carburetor mixture to such an extent that there is considerable likelihood that the engine, which has not yet been brought up to operating temperatures, will stall. The provision of the dash pot in this connection is to prevent the sudden rush of air as soon as the engine fires from opening the choke valve any appreciable amount beyond the position which the valve takes in response to the thermostat connected

therewith. As the motor temperature slowly rises the thermostat gradually opens the choke valve to the proper position, and since this movement is more or less gradual the dash pot does not restrain the same.

Another object of the present invention is the provision of such restraining means operative to prevent the over-balanced carburetor choke valve from opening under any sudden rush of air drawn into the carburetor, as by the initial firing of the engine or by sudden acceleration, in connection with means which is responsive to the initial firing of the engine and is operative immediately, or practically so, to adjust the position of the choke valve to meet this condition, that is, the carburetor choke valve is changed from its cranking position to a running position without relinquishing the control of the temperature responsive means on the choke valve and, at the same time, without having the sudden rush of air past the overbalanced valve disturb these adjustments, this latter feature being accomplished by the inclusion of the dash pot referred to.

This application is an improvement on applicants' copending application Serial No. 585,510 and the claims presented in this application relate only to such subject matter as is not disclosed in the earlier case, the broad claims readable on subject matter common to the two applications being presented in the earlier application.

These and other objects of the present invention will be apparent from the following detailed description of the preferred form in which the principles of the present invention have been embodied, taken in conjunction with the accompanying drawings illustrating such embodiment.

In the drawings:

Figures 1 and 3 show an engine having a carburetor provided with our automatic choke;

Figure 2 is an enlarged fragmentary section taken along the line 2—2 of Figure 1;

Figure 4 is a section taken on the line 4—4 of Figure 1;

Figure 5 is a section taken on the line 5—5 of Figure 4, showing the mounting or base plate and the shaft bracket;

Figure 6 is a section taken along the line 6—6 of Figure 4;

Figure 7 is a view taken along the line 7—7 of Figure 3, looking in the direction of the arrows;

Figure 8 is a fragmentary section taken on the line 8—8 of Figure 6;

Figures 9 and 10 are views of the suction responsive bellows;

Figures 11 and 12 are views of the dash pot piston; and

Figure 13 illustrates a form of the present invention in which the means actuated when the engine starts is a simple connection with the starting motor control, rather than a suction responsive bellows.

Referring now to the drawings, Figures 1 to 3 show the application of the present invention to an internal combustion engine 1 having an intake manifold 2 and an exhaust manifold 3 interconnected in such a way that the exhaust gases passing out through the exhaust manifold 3 flow around the central portion of the intake manifold, indicated at 4 in Figures 1 and 2. A down draft carburetor 5 is mounted at the inlet 4 of the intake manifold 2, as best shown in Figure 1, and includes a draft tube 6 bolted, as at 7, to the upper portion of the exhaust manifold 3 surrounding the inlet section 4 of the intake manifold 2. The carburetor 5 is provided with an air inlet 8 which is controlled by a choke valve or air valve 9 of the unbalanced butterfly type which tends to open under suction. The choke valve 9 is mounted on a shaft to the outer end of which is fixed a valve arm 10 by which the position of the choke valve 9 may be controlled, either manually or automatically.

According to the principles of the present invention, the choke valve 9 is controlled automatically according to the several factors to which the carburetor 5 is subjected. The automatic choke is indicated in its entirety by the reference numeral 15 and comprises a casing 16. The latter includes a base or mounting plate 17 having a flange section 18 by which the automatic choke control 15 is mounted, as by bolts 19, onto the exhaust manifold 3, in the position shown in Figures 1 to 3. The mounting plate 17 carries a sheet metal shell 21 at the upper portion of which is disposed a cap 22. A pair of screws 23 disposed in openings in the cap 22 and threaded into the mounting plate 17 serve to hold the shell 21 and cap 22 in place on the mounting plate 17. A bracket 25 is secured, as by welding or the like, to the bottom of the mounting plate 17, and the bracket 25 includes a pair of downwardly disposed ears 26 in which a shaft 27 is journaled by any suitable form of bearing means. The shaft 27 extends outwardly of the bottom cover 28, which encloses the shaft 27 and operating parts associated therewith, and an arm 30 is fixedly connected to the extended end of the shaft 27. A link 31 serves to connect the outer end of the arm 30 with the choke valve arm 10, whereby the position of the shaft 27 serves to control the position of the choke valve 9.

The position of the shaft 27 is controlled by separately operable mechanisms including a suction operated bellows 38, a thermostat 37, and a motion restraining dash pot 39. Referring first to the bellows mechanism 38, the mechanism includes a flexible bellows 40 having its upper end sealed by a cap 41 which is, in turn, securely fastened, as by soldering, welding or the like, to the cover or cap 22 of the casing 16. The bellows cap 41 includes a central extension 44 of cylindrical formation which is open at its inner end and receives a fitting 45 which includes a central section 46 having a tapered bore 47, the outer portion of the central section 46 being screw threaded, as at 48, to receive a metering pin 50 having a kerf 51 and a lock nut 52 by which the metering pin may be securely fastened in adjusted position. The inner portion of the

metering pin 50 includes a tapered section 54 which, corresponding to the taper of the fitting section 46, serves to increase or decrease the effective size of the passageway between the fitting 45 and the interior of the bellows 40. The fitting 45 also includes a laterally extending coupling 58 with which one end of a small tube 61 is connected as by a bushing 62. The lower or opposite end of the tube 61 terminates in a head 63 which registers with an opening 64 formed in the 10 casting of which the intake and exhaust manifolds are constructed and which communicates at its inner end with the intake manifold 2, whereby the intake suction of the engine 1 is communicated to the interior of the bellows. Preferably, the end 63 of the tubing 61 is so constructed and disposed that when the bolts 19, by which the automatic choke device is mounted on the exhaust manifold 3, are tightened, the tube 61 is effectively sealed with respect to the bore 20 64. It is to be understood, of course, that any other means for communicating the suction of the intake manifold 2 to the interior of the bellows 40 may be employed.

The end of the bellows 40 adjacent the coupling 25 45 is, as described, sealed to the casing cap piece 22, and the other end of the bellows is movably mounted within the casing and is sealed, as by soldering, to a closure cap 70 to which a bracket 71 is fastened. The bracket 71 includes a pair of ears 73 and the latter are provided with oppositely arranged lateral extensions 74, each of which carries an adjusting set screw 75 held in adjusted position by means of a retainer spring 76. The ears 73 are apertured to receive a pivot pin 35 or rivet 80 by which a link 81, connected to the outer end 82 of the thermostat 37 as will be referred to later, is connected to be shifted by the operation of the bellows 40. This end of the bellows, which is movable, is limited in its movements to an inner position, corresponding to the retracted position of the bellows due to the application of suction to the interior thereof, and an outer position to which the movable end of the bellows is moved by a spring 85 disposed on the interior of the bellows and held in place at its upper end by being disposed around the central portion 44 of the upper closure cap 41. The lower end of the spring 85 is disposed over a boss or projection 87 formed in the lower bellows cap 70.

The lower position of the bellows 40 is shown in Figure 2 and in this figure it will be observed that the lower position of the bellows is determined by the engagement of the bellows cap 70 with the upper surface of the mounting plate 17. When the bellows is subjected to suction on its interior, the bellows is collapsed or retracted against the tension of the spring 85 and the movable end of the bellows is drawn upwardly 60 until the adjusting set screws 75 engage the abutments 88, thus limiting the retracted position of the bellows so that, even with increasing amounts of suction applied to the bellows, the lower or movable end thereof is held against further movement. This limitation of the movements of the bellows to two definite positions by suitable stop means will be referred to later.

Referring now to the thermostat 37, it will be observed from Figure 2 that the inner end 88 70 of the thermostat 37 is anchored in a slot formed in the shaft 27. The thermostat 37 is coiled about the shaft 27 a number of times and has its outer end 82 connected with the lower end of the link 81, as mentioned above, by means of a 75

pin 101. By virtue of this construction, the movements of the bellows 40 are communicated to the shaft 27 through the interposed thermostat 37. The bellows 40 is a suction operated device and the thermostat 37 is a temperature responsive device, and it will be noted that these devices are arranged in series so far as their control of the shaft 27 is concerned. The casing 28, secured to the lower side of the mounting plate 17, encloses the shaft 27, the thermostat 37 and the link 81, but the heat from the exhaust manifold 3 is transmitted to the region of the thermostat 37 by means of a plate 110 formed of material of high conductivity and having a curved section 111 disposed closely adjacent the thermostat 37 and with ends 112 and 113 passed through suitable slots formed in the cover 28 and disposed in parallel relation with respect thereto so as to be in contact with the outer wall of the exhaust manifold 3. If desired, the heat transmitting member 110 may be insulated from the cover 28 proper by suitable insulating means, such as a sheet of asbestos or the like. Small ears 115 engage the inner surface of the casing 28 and hold the member 110 in position.

The dash pot device 38 is best shown in Figure 4 and will be seen to comprise a cylinder 120 disposed within the casing 16 and including a movable piston 121 having at its upper end a check valve 122 which opens upwardly, against the tension of a light spring 123, to permit the free flow of air into the space above the piston 121 when the same moves downwardly in the cylinder 120 but which closes when the piston 121 tends to move upwardly so that there is a cushion of air above the piston 121 which escapes slowly between the piston 121 and the walls of the cylinder 120. To this end, the diameter of the piston 121 is arranged to be slightly less than the interior diameter of the cylinder 120 to provide for the desired current. A leakage groove 124 is formed in the cylinder 120 and has an increasing depth toward the upper end of the cylinder so that the escape of air around the piston 120 is more rapid when the piston is in its upper position than when it is in its lower position, the position indicated in Figure 4. The cylinder 120 is closed by a cap 125 which is disposed in a groove in the upper end of the cylinder and held therein by any suitable means.

The lower end of the piston 121 is formed with a groove 126 in which is fixed a disk 127 having a pair of lugs 128 cut and bent downwardly therefrom and apertured to receive a pivot pin 130 to which the upper end of a link 131 is connected. The lower end of the link 131 is bifurcated and connected, by means of a pin 134, with the outer end of an arm 135 rigidly secured to the end of the shaft 27 opposite the end to which the thermostat 37 is connected, as best shown in Figure 6. Since the arm 135 is rigidly secured to the shaft 27 and since the piston 121 is link connected with the arm, it will be seen that the dash pot device just described serves to oppose any sudden movement of the shaft 27, and since the choke valve is connected to this shaft by the link 31, likewise any sudden movement of the choke valve 9 is restrained by the dash pot, the greater restraint being imposed upon the choke valve, by virtue of the tapered groove 124, in the lower position of the piston 121, which corresponds to the closed or nearly closed position of the choke valve 9.

The cylinder 120 is loosely disposed within the casing 16, and the lower or inner end of the cylinder 120 is provided with a flange 140 which is

received within an opening formed in one side of the mounting plate 17, and the bracket 25, which includes a portion covering the cylinder receiving opening, is provided with an opening smaller than but in registry with said cylinder receiving opening, as indicated at 141. The ears 128 extend through the opening 141, as best shown in Figure 4. The mounting plate 17 is also provided with a second opening 142 registering with the opening in the mounting plate 17 through which the ears 73 and the link 81 extend, as best shown in Figure 2. These registering openings are somewhat elongated in formation, as indicated at 145, and adjacent the elongated portions 145 the abutment stops 90 are formed. The elongations 145 provide for the convenient assembly of the device, in that by turning the bellows device 36 through a small angle, the lateral extensions 74 will pass downwardly through the opening portions 145, and then the bellows assembly can be rotated back to its position to dispose the adjusting screws 75 in proper position with respect to the abutment stops 90. Preferably, also, to facilitate assembly, one of the bracket ears 26 is provided with a larger bearing opening than the other, the smaller one receiving the reduced end 150 of the shaft 27 while the larger opening receives a bearing bushing 151 which is adapted to be inserted over the other end of the shaft 27 after the latter has been disposed in the bearing openings of the bracket ears 26. After the bearing bushing 151 has been inserted over the arm end of the shaft 27 and disposed in the opening provided therefor in the associated bracket ears 26, a retainer clip 152 in the form of a spring is engaged in a groove formed in the bushing 151 and serves thereby to hold the latter in position. Preferably, also, the outermost end of the shaft 27 is formed with a flattened section and the choke valve operating arm 30 is also provided with a similar section so that the angular relation between the arm 30 and the shaft 27 about the axis of the latter is determined. The choke valve operating arm 30 is securely clamped around this end of the shaft 27 by a clamping screw 155. The bottom cover 28 may be held in place against the lower side of the mounting plate 17 by any suitable means, such as a screw 157 extending through an opening in the bottom of the cover 28 and engaging a threaded opening in the mounting plate 17 or in the bracket 25 secured to the lower space thereof.

The operation of the device described above is substantially as follows. The bellows device 36 has its lower movable end 70 held against the upper face of the mounting bracket 17 by the spring 85 so long as there is no suction in the intake manifold 2, and this disposes the outer end 82 of the thermostat 37 in the lower position of the two positions it is desired to occupy, the upper position being when the bellows 40 is drawn upwardly by the application of suction so that the adjusting screws 75 engage the abutments 90. When outside temperatures are low and when the outer end 82 of the thermostat 37 is in its lower position, the position of the shaft 27 is such that the choke valve 9 is held by the thermostat 37 in its closed or substantially closed position. This adjusts the carburetor 5 for cranking under low temperature conditions. As the starting motor is energized and the engine 1 cranked, a small amount of suction will be established in the intake manifold 2, and this will serve to contract the bellows 40 slightly so as to raise the link 81

and the outer end of the thermostat 32. This will rock the shaft 27 a corresponding amount since the temperature to which the thermostat 37 is subjected has not been changed. Now as the engine fires and begins to run under its own power, the suction in the intake manifold 2 is materially increased the moment the engine fires. This sudden increase in the suction is immediately applied to contract the bellows 40, the rate of application being governed by the setting of the metering pin 58 which serves, in the first instance, to prevent the sudden building up of suction in the intake manifold 2 from swinging the shaft 27 to suddenly open the choke valve 8, it being obvious that the farther in the metering pin 58 is adjusted, the greater the restriction established thereby will be and the greater will be length of time required for the suction to lift the bellows 40. However, the moment the engine fires the suddenly created suction in the intake manifold 2 and the sudden rush of air past the choke valve 8 in the air inlet 8 of the carburetor tends to swing the valve to its open position, as a result of the use of the overbalanced type of valve. At this moment, however, the dash pot device 38 comes into action and, being directly connected with shaft 27, which in turn is directly connected with the arm 18 of the choke valve, the dash pot device is immediately effective to prevent any sudden opening of the choke valve the moment the engine begins to fire. In the absence of a dash pot or the equivalent, the moment the engine would begin to fire, the sudden rush of air would swing the choke valve open and the fuel mixture would be too lean, with consequent danger of the engine stalling. The dash pot, constructed according to the principles of the present invention, effectively prevents the sudden opening of the choke valve but allows the same to slowly open as the engine warms up, the gradual opening of the choke valve being predetermined by the characteristics of the thermostat 37. According to the principles of the present invention, therefore, as soon as the engine begins to fire, the bellows device 38 operates to shift the outer end 82 of the thermostat through a fixed distance, corresponding to the spacing between the stops associated with the movable end of the bellows, but neither this sudden movement nor the effect of the sudden application of suction to the choke valve itself will cause any immediate or instantaneous change in position of the choke valve, due to the restraining action of the dash pot, particularly the more effective restraint established by the dash pot in the lower positions of the piston 121. Gradually, however, as the motor warms up and the thermostat 37, reacting against the lower end of the link 81, exerts a force to rotate the shaft 27 and also as the dash pot gradually gives way to the effect of the air pressure on the choke valve 8 itself, the latter opens to progressively reduce the amount of choking at practically exactly the rate best suited to adjust the carburetor for the change in temperature and pressure conditions.

As the engine continues in operation and as the temperature thereof increases, the effect of the thermostat 37 is to gradually open the choke valve, to which gradual movement the dash pot offers substantially no resistance. The metering pin 58 and associated parts are such that minor fluctuations in the intake suction do not affect the setting of the outer end of the thermostat 32, and even though the intake suction should drop appreciably for a short length of time, the lower

end of the bellows 40 will not move downwardly away from the abutments 86 for an appreciable length of time, due to the fact that the diameter of the bellows 40 and the restriction established by the metering pin 58 serve to prevent the bellows from returning the end 82 of the thermostat to cranking position, that is, to its lower position, unless the cessation of suction continues for some little time. However, if the engine should stall and the suction in the intake manifold be cut off for a short time, then the bellows 40 acting through the thermostat 37 as a lever, operates to the return choke valve toward its cranking position. However, as long as the engine 1 is actually running, the bellows 40 serves to hold the screws 15 75 up against the abutments 86, thereby holding the thermostat end 82 in running position.

The sudden building up of the intake suction after the motor fires and begins to run is only one means for shifting the thermostat device 37 from its cranking position to its starting position or, in other words, for automatically shifting the choke valve 8 from its cranking position to its starting position. Other means may be employed which in a general sense are responsive to cranking conditions or adjustments of the engine as compared with running conditions or adjustments. For example, the end 82 of the thermostat may be automatically shifted by suitable connection with the starting motor of the engine 1 or any of the associated controls, as illustrated in Figure 13. In this figure the bellows 36 and associated connections have been omitted. Instead, the end 82 of the thermostat is connected to the upper end of a Bowden wire 160 which is suitably enclosed in a casing 161. The lower end of the wire is connected by a lug 163 with the plunger 162 of the mechanism which controls the starting motor for the engine 1. In operation, when it is desired to start the engine 1, the plunger 162 is pressed downwardly, the position shown in Figure 13, by any suitable means so as to cause the starting motor 164 to crank the engine 1. The downward movement of the plunger 162 to the position shown in Figure 13 exerts a pull 45 on the wire 160, and this swings the thermostat 37 downwardly substantially to a position like that shown in Figure 2. As soon, however, as the engine begins to fire, the plunger 162 is released and the spring 165 forces the same back 50 to its original position. This movement of the plunger 162 is transmitted through the wire 160 to the end 82 of the thermostat 37 and moves the same through substantially the same extent that the thermostat in Figure 2 is shifted by the contraction of the bellows 38 which, as described above, is also responsive to the starting of the engine 1. Thus, where in one case I have utilized the increase in suction to cause a shift of the thermostat 37 whenever the engine begins to run, 60 and in Figure 13 I have illustrated a construction in which the movement of the starting motor control mechanism from a cranking position to a position corresponding to the running of the engine for causing the same shift of the associated 65 thermostat, it is to be observed that in each case the parts constitute means for shifting the thermostat from one position to another whenever the engine 1 begins to fire.

The dash pot device 38, both in the form of the 70 invention shown in Figure 2 and the form shown in Figure 13, also serves another important function in automatically controlling carburetor adjustments. The primary object of the dash pot is to prevent sudden fluctuations of air pressure on 75

the choke valve 9 from shifting the same out of the desired position to which it has been moved by the temperature responsive thermostat 37. For example, after a cold motor has been started 5 and has been running for a short length of time, it may be that sudden acceleration of the motor and the resulting rush of air past the choke valve 9, would tend to swing the same to an open position which would thin the fuel mixture to such 10 a point that the motor would not operate properly. The dash pot device 38 under such conditions functions to prevent such sudden opening of the choke valve and therefore, operates during periods of acceleration to maintain the proper 15 fuel ratio. In this connection, it is to be noted, that the dash pot 38 is more effective in its lower positions, which correspond to the more closed positions of the choke valve, than when the piston 121 is in its upper range of movements.

20 While we have shown and described above the preferred structure in which the principles of the present invention have been embodied, it is to be understood that our invention is not to be limited to the specific details shown and described, but that, in fact, widely different means may be employed in the practice of the broader aspects of our invention.

What we claim, therefore, and desire to secure by Letters Patent is:

30 1. An automatic choke for carburetors for internal combustion engines in which the carburetor is provided with an unbalanced air valve, said automatic choke comprising a casing, a shaft journaled in one section of said casing and having an arm adapted to be connected with said air valve, a thermostat anchored at one end to said shaft, a bellows disposed in the other section of said casing and having one end fixed thereto and the other end movable, means connecting the 35 movable end of said bellows with the other end of said thermostat, whereby the movements of said bellows shift said shaft and arm carried thereby by shifting said thermostat, a second arm disposed in the first section of said casing and rigidly connected with the shaft therein, means in the second section of said casing serving as a dash pot and operatively connected with said second arm, and means adapted to 40 communicate the intake suction of the engine to said bellows.

50 2. An automatic choke for carburetors for internal combustion engines in which the carburetor is provided with a choke valve, said automatic choke comprising a casing, a shaft journaled therein and provided with an arm secured thereto and adapted to be connected with said choke valve to control the position thereof, a thermostatic spring connected at one end with said shaft, a bellows carried by said casing and having a movable end connected with the other end of said thermostatic spring, means serving as a pair of spaced stops for the movable end of said bellows to limit the movement thereof, spring means tensioned to shift the movable end of said bellows against one of said stop means, means providing for the communication of intake suction from the engine to said bellows, and means incorporated therein and including a metering pin for restricting the application of suction to said bellows, the intake suction acting to draw the movable end of said bellows against the other of said stop means, the tension of said spring means and the setting of said metering pin being correlated with the amount of intake suction so that the spring will not move the mov-

able end of the bellows against said first stop means for a length of time greater than that required for the suction to draw the movable end of the bellows from said first stop means up against said second stop means.

5 3. The combination for use with an internal combustion engine having an exhaust manifold and an intake passageway, and a carburetor having an air valve which tends to open by suction in said intake passageway, of a casing adapted to be secured to said exhaust manifold, a shaft journaled in said casing and having an arm secured thereto and connected with said air valve, a thermostat disposed in said casing and connected at one end with said shaft, means providing for the transmission of heat from the exhaust manifold to said thermostat, a bellows carried by said casing and having a movable end connected with the other end of said thermostat, stop means limiting the movements of said movable end in both directions, one of said stop means being adjustable, and conduit means leading from the interior of said intake passageway to the interior of said bellows.

20 4. The combination for use with an internal combustion engine having an exhaust manifold and an intake passageway, and a carburetor having an air valve which tends to open by suction in said intake passageway, of a casing adapted to be secured to said exhaust manifold, a shaft 30 journaled in said casing and having an arm secured thereto and connected with said air valve, thermostat disposed in said casing and connected at one end with said shaft, means providing for the transmission of heat from the exhaust manifold to said thermostat, a bellows carried by said casing and having a movable end connected with the other end of said thermostat, stop means limiting the movements of said movable end in both directions, one of said stop means being adjustable, conduit means leading from the interior of 35 said intake passageway to the interior of said bellows, a metering pin disposed in said conduit means for governing the rate of application of the intake suction to said bellows, and a dash 40 pot operatively connected with said shaft and arranged to resist the rotation thereof in the direction in which the contraction of said bellows, due to the application of suction thereto, tends to move the same.

50 5. The combination for use with an internal combustion engine having an exhaust manifold and an intake passageway, and a carburetor having an air valve which tends to open by suction in the intake passageway, of a casing 55 adapted to be mounted on said exhaust manifold, a rotatable shaft journaled in said casing and having an arm adapted to be connected to said air valve to position the same, a thermostat mounted on said arm, means providing for the transmission of heat from the exhaust manifold to said thermostat, a dash pot connected with said shaft and adapted to resist certain rotation of said shaft in a direction which corresponds to the opening of said air valve, a movable member connected with the outer end of said thermostat and arranged, by change in the position of the latter, to change the position of said air valve, means providing definite stops 60 in both directions for said movable member, one position corresponding to the desired position of said air valve during cranking of the engine and the other position corresponding to the desired position of the air valve when the engine 65

begins to fire, and means for shifting said movable member from one position to another.

6. The combination for use with an internal combustion engine having an exhaust manifold and an intake passageway, and a carburetor having an air valve which tends to open by suction in the intake passageway, of a thermostat, means connecting one end of said thermostat with the air valve to govern the position of the latter, means subjecting the thermostat to the heat from the exhaust manifold, a dash pot for resisting sudden opening thereof, said dash pot comprising a cylinder, a piston slidably therein and connected to the air valve, said cylinder having a tapered groove formed in the inner wall thereof adjacent the piston to vary the resistance of the dash pot to movement of the valve, a movable anchoring member to which the other end of the thermostat is connected, stop means providing two definite positions for said movable member, one position corresponding to the position of the air valve when the engine is being cranked and the other position corresponding to a position of the air valve when the engine begins to run, means biasing said movable member to yieldingly hold the same in one position, and means for moving said movable member from said one position to the other position.

20 7. The combination for use with an internal combustion engine having an exhaust manifold and an intake manifold, and a carburetor having an air valve which tends to open by suction in the intake manifold, of a casing adapted to be secured to the exhaust manifold and including a lower portion, a shaft journaled in said lower portion, an arm on the outer end of said shaft operatively connected with the air valve of said carburetor, means providing for the transmission of heat from said exhaust manifold to the lower portion of said casing, a thermostat anchored at its inner end to and coiled around said shaft and subjected to the heat from said exhaust manifold, an arm fixed to said shaft in the lower portion of said casing, a pair of chambers formed in the upper portion of said casing and disposed alongside one another, a dash pot piston mounted in one of said chambers and connected with said last mentioned arm, valve means carried by said tension and providing for the restraint of movement of said arm and shaft in one direction only, a bellows disposed in the other of said chambers and anchored at its upper end to said casing, the lower end being movable therein, link means connecting the movable end of said bellows with the outer end of said thermostat, means carried by said casing and serving as a pair of stops limiting the movement of the outer end of said thermostat in both directions, and means subjecting the interior of said bellows to the suction in said intake manifold.

8. An automatic choke for carburetors for internal combustion engines in which the carburetor is provided with an unbalanced air valve, said automatic choke comprising a casing, a shaft journaled in one section of said casing and having an arm adapted to be connected with said air valve, a thermostat anchored at one end to said shaft, a bellows disposed in the other section of said casing and having one end fixed thereto and the other end movable, and means connecting the movable end of said bellows with the other end of said thermostat, whereby by shifting said thermostat the move-

ment of said bellows shifts said shaft and the arm carried thereby.

9. An automatic choke for carburetors for internal combustion engines having an exhaust manifold and in which the carburetor is provided with an unbalanced air valve, said automatic choke comprising a mounting bracket adapted to be secured to said exhaust manifold and having depending ears, a shaft journaled in said ears and having an arm adapted to be connected with said carburetor air valve, a thermostat anchored at one end to said shaft and disposed on the under side of said bracket, a bellows disposed on the other side of said bracket, an upper casing section mounted on said bracket and enclosing said bellows, the latter having one end fixed to said casing and the other end movable, a lower casing section enclosing said shaft and thermostat, means connecting a movable end of said bellows with the other end of said thermostat, whereby movement of said bellows shifts said shaft and the arm carried thereby, and means serving to transmit heat from said exhaust manifold to said thermostat.

10. An automatic choke for carburetors for internal combustion engines in which the carburetor is provided with a choke valve, said automatic choke comprising a casing, a shaft journaled therein and provided with an arm secured thereto and adapted to be connected with said choke valve to control the position thereof, a thermostatic spring connected at one end with said shaft, a bellows carried by said casing and having a movable end connected with the other end of said thermostatic spring, means serving as a pair of spaced stops for the movable end of said bellows to limit the movement thereof, means tending to hold the movable end of said bellows against one of said stop means, and means providing for the communication of intake suction from the engine to said bellows.

11. The combination for use with an internal combustion engine having an exhaust manifold and an intake passageway, and a carburetor having an air valve which tends to open by suction in said intake passageway, of a casing adapted to be secured to said exhaust manifold, a shaft journaled in said casing and having an arm secured thereto and connected with said air valve, a thermostat disposed in said casing and connected at one end with said shaft, means providing for the transmission of heat from the exhaust manifold to said thermostat, a bellows carried by said casing and having a movable end connected with the other end of said thermostat, stop means limiting the movements of said movable end in both directions, and conduit means leading from the interior of said intake passageway to the interior of said bellows.

12. The combination for use with an internal combustion engine having an exhaust manifold, and a carburetor having an air valve which tends to open by suction in said intake passageway, of a casing adapted to be secured to said exhaust manifold, a shaft journaled in said casing and having an arm secured thereto and connected with said air valve, a thermostat disposed in said casing and connected at one end with said shaft, means providing for the transmission of heat from the exhaust manifold to said thermostat, a bellows carried by said casing and having a movable end connected with the other end of said thermostat, and means operable through said bellows when the engine begins to run for imparting a given shift to the position of said ther-

mostat, independent of the temperature of said exhaust manifold.

13. The combination for use with an internal combustion engine having an exhaust manifold and an intake passageway, and a carburetor having an air valve which tends to open by suction in the intake passageway, of a spring thermostat, means connecting one end of said thermostat with the air valve to govern the position of the latter, means subjecting the thermostat to the heat from the exhaust manifold, a movable anchoring member to which the other end of the thermostat is connected, stop means providing two definite relatively fixed positions for said movable member, one position corresponding to the position of the air valve when the engine is being cranked and the other position corresponding to a position of the air valve when the engine begins to run, means for moving said movable member from said one position to the other position, dash pot means connected to said air valve for cushioning the movement of said air valve against the tension of said spring thermostat occasioned by variations in suction in the intake passage, and means for reducing the cushioning effect of said dash pot as said valve is moved toward open position.

14. In a charge forming device for internal combustion engines, means for automatically determining the ratio of air to fuel in the mixture supplied to such engine comprising a suction-operated air valve for regulating the supply of air, thermally responsive means operative to move said air valve toward open position upon increase of engine temperature and a dash pot operable to oppose the movement of said valve toward open position upon increase in the suction effective on such valve, and means for varying the resistance of the said dash pot as the valve moves toward open position.

15. In a charge forming device for internal combustion engines, means for automatically determining the ratio of air to fuel in the mixture supplied to such engine comprising a suction-operated air valve for regulating the supply of air, thermally responsive means operative to move said air valve toward open position upon increase of engine temperature and a dash pot operable to oppose the movement of said valve toward open position upon increase in the suction effective on such valve, and means for progressively reducing the resistance of the dash pot as the valve moves toward open position comprising a tapered slot in the wall of the dash pot cylinder to permit escape of air therefrom.

16. An automatic choke mechanism for the charge forming device of an internal combustion engine having an intake manifold provided with a heating chamber for heating the combustible mixture supplied to the engine and comprising, in combination, a mixture proportioning means, a control unit for operating said mixture proportioning means and including a housing, thermally responsive means mounted in said housing adapted to position said mixture proportioning means in accordance with engine temperature, a suction operated means also positioned within said housing and adapted to vary the setting of the mixture proportioning means as determined by said thermally responsive means in accordance with engine suction, means for securing said housing directly to the wall of the heating chamber in such position that the thermally responsive means is relatively close

to said wall and a metallic heat conducting element between the wall and the thermostat.

17. An automatic choke mechanism for the charge forming device of an internal combustion engine having an intake manifold provided with a heating chamber for heating the combustible mixture supplied to the engine and comprising, in combination, a mixture proportioning means, a control unit for operating said mixture proportioning means and including a housing, a suction operated element in said housing for operating said mixture proportioning means, thermally responsive means in said housing for determining the position of said mixture proportioning means in accordance with engine temperature to modify the position of said mixture proportioning means as determined by temperature, a suction passage for communicating the suction of the intake manifold to said suction operated element, and a manually adjustable metering valve in said suction passage to control the effective area thereof and to vary the effect of engine suction on said mixture proportioning means.

18. An automatic choke mechanism for the charge forming device of an internal combustion engine having an intake manifold provided with a heating chamber for heating the combustible mixture supplied to the engine, and comprising, in combination, a mixture proportioning means, a control unit for operating said mixture proportioning means and including a housing, a thermally responsive element in said housing adapted to hold said mixture proportioning means in position to form a rich mixture when the temperature is low, a suction operated element in said housing adapted to move said mixture proportioning means through the medium of the thermostat toward position to form a lean mixture as the engine suction increases, a suction passage for communicating the manifold suction to said suction operated element and a manually adjustable metering pin in said passage to control the suction effect on said suction operated element.

19. An automatic choke mechanism for the charge forming device of an internal combustion engine having an intake manifold provided with a heating chamber for heating the combustible mixture supplied to the engine and comprising, in combination, a mixture proportioning means, a control unit for operating said mixture proportioning means and including a housing, a suction operated element adapted upon increase of engine suction to move the mixture proportioning means toward a position to form a lean mixture and upon decrease of suction to control the movement of said mixture proportioning means toward a position to form a rich mixture, a suction conduit to communicate manifold suction to the suction operated element, said conduit having a portion with a gradually tapered wall forming a valve seat, a manually adjustable valve received within the conduit and extending longitudinally thereof, said valve having a surface substantially parallel to said valve seat, whereby adjustment of said valve may effect minute variations in the area of the passage between said valve and seat to accurately determine the rate of movement of the mixture proportioning means as brought about by variations in suction.

20. An automatic choke mechanism for the charge forming device of an internal combustion engine having an intake manifold provided with a heating chamber for heating the combustible

- 5 mixture supplied to the engine, and comprising, in combination, a mixture proportioning means, a control unit for operating said mixture proportioning means and including a housing, thermally responsive means in said housing adapted to 5
10 operate the mixture proportioning means, means directly securing said housing to the wall of said heating chamber, and a metallic gasket adapted to be secured between said housing and the heating chamber, said gasket being provided with a projecting surface extending toward said thermally responsive means whereby said gasket acts 10
15 as a metallic heat conductor for conducting heat from said heating chamber to the thermally responsive means.
- 15 21. An automatic choke mechanism for the charge forming device of an internal combustion engine having an intake manifold provided with a heating chamber for heating the combustible mixture supplied to the engine, and comprising, in combination, a mixture proportioning means, a control unit for operating said mixture proportioning means and including a housing, thermally responsive means in said housing adapted 20
25 to operate the mixture proportioning means, means directly securing said housing to the wall of said heating chamber, and a metallic gasket adapted to be secured between said housing and the heating chamber, said gasket being provided with a projecting surface which extends partially 25
30 around the thermostat, whereby said gasket acts as a metallic conductor of heat from the heating chamber to the thermally responsive means and also as a shield for said thermally responsive means.
- 35 22. An automatic choke for carburetors for internal combustion engines in which the carburetor is provided with an unbalanced air valve, comprising the combination of thermostat means responsive to engine temperature, means yieldingly connecting the thermostat means with said valve for shifting the same to a position cor- 40
45
- responding to engine temperature and providing for movement of the valve relative to said thermostat means throughout the range of the latter under the influence of air pressure against the valve, dash pot means having a rigid connection with said valve to prevent sudden changes of air velocities from shifting said valve out of the position determined by said spring thermostat means and means for reducing the resistance offered by the dash pot to movement of the valve 10
15 as the said valve is moved toward its open position.
23. An automatic choke for carburetors for internal combustion engines in which the carburetor is provided with an unbalanced air valve tending to open by the flow of air past said valve, said automatic choke comprising the combination of thermostat means responsive to engine temperature, means yieldingly connecting the thermostat means with said valve for shifting the same to a position corresponding to engine temperature, means operable between two definite limits intermediate the range of movement of said valve for shifting the latter from one of said definite positions to the other when the engine begins to run, dash pot means having a rigid connection with said valve and adapted to oppose sudden movements of the valve inside said limits of movement thereof whereby the opening of said valve under the influence of air flow past the same and under the influence of sudden decreases in the intake suction is resisted by said dash pot means and means for reducing the resistance offered by the dash pot to movement of the valve as the said valve is moved toward its open position.
